UNITED STATES PATENT OFFICE.

ANDREW PLECHER, OF LAS ANIMAS, COLORADO.

TELEPHONE-TRANSMITTER.

1,193,184.

Specification of Letters Patent.

Patented Aug. 1, 1916.

Continuation of application Serial No. 633,461, filed June 16, 1911. This application filed April 19, 1912.
Serial No. 691,892.

To all whom it may concern:

Be it known that I, ANDREW PLECHER, a citizen of the United States, residing at Las Animas, in the county of Bent and State of Colorado, have invented a new and useful 5 Telephone-Transmitter, of which the following is a specification.

This invention has reference to improvements in telephone transmitters, and its object is to produce a transmitter in which is 10 combined the clearness and distinct transmission of a Blake transmitter with the volume and wide range of the Hunnings transmitter with certain advantages possessed by 15 neither.

In accordance with one form of the present invention the speech receiving diaphragm is not supported at the periphery after the common practice, but is free to 20 vibrate at the periphery, being supported at the central portion, and in order that the diaphragm may respond vigorously to both the fundamentals of the tones of the human voice and also to the overtones or 25 harmonies, the diaphragm is multi-tuned, so that different parts of it have different natural rates of vibration corresponding to the fundamentals and the overtones of speech and other sounds uttered against the dia- 30 phragm, wherefore the sound components are to a large extent individually strengthened as compared to sound or speech transmission through diaphragms as ordinarily constructed. The multi-tuning of the dia- 35 phragm is advantageous when employed in connection with other features of the invention, but improved results may be obtained in speech or sound transmission when the diaphragm is not especially tuned, nor need 40 the diaphragm be supported centrally and free peripherally, but the contrary may be true with good results. When the dia- 45 phragm is multi-tuned it is customary to employ a metallic diaphragm free to vibrate at the periphery and locally tuned about the marginal portion, while in the path of the peripheral portion of the diaphragm an electrical conducting medium is supported in a manner to be engaged by the diaphragm, the 50 support being of a more or less elastic nature, but loose granules, such as are employed in connection with the Hunnings transmitter, are avoided, and the conducting medium opposed to the diaphragm is cus-

tomarily film-like either in the form of a 55 metallic leaf, or in the form of fine powder, or granules of metal or carbon caused to be strongly adherent to the carrying surface, which latter, however, need not be conduct- 60 ing.

In another and important form of the invention the use of a metallic diaphragm is avoided, and in its place there is provided a membrane which may be stretched until sufficiently taut for the purposes of the invention, and this diaphragm membrane is provided on one face with a conducting film which may be quite thin, and yet, because of its large surface, will provide ample conduct- 65 ing capacity for heavier currents than 70 are possible with the usual granular or Hunnings form of transmitter. Opposed to the conducting face of the membrane, which face is remote from that against which speech is uttered, there is provided a con- 75 ducting plate which may be polished and then cross-hatched or otherwise treated to provide a multitude of points which not only prevent sticking of the electrodes made up of the plate and conducting film, but provide 80 many points from which electrical dis- charges may readily pass.

By adjusting the back plate, as it may be called, into proper relation to the conducting surface of the membrane, no current will 85 pass when the parts are at rest, but as soon as speech, which may be taken as typical of any sound to be transmitted, is uttered against the diaphragm, the latter is vibrated into and out of contact with the back plate, 90 thus establishing make-and-break transmission with the great variation in resistance of such a type of telephonic transmission, but while there is mechanical make-and-break in the circuit, electric make-and-break is avoid- 95 ed, for the broad surface of the conducting film of the membrane and the broad surface of the back contact at once establish condenser conditions, the discharges of which maintain the continuity of the circuit elec- 100 trically, thereby establishing in effect a variable contact transmitter wherein the variations of resistance is far in excess of the best form of commercial telephone transmitters, and the distant receiver is actuated with 105 commensurate vigor.

The invention will be best understood from a consideration of the following de-

tailed description taken in connection with the accompanying drawings forming a part of this specification, with the understanding that while in the drawings different embodiments of the invention are disclosed, the invention is not confined to any strict conformity with the showing of the drawings, but may be embodied in any manner which does not mark a material departure from the 10 salient features of the invention.

In the drawings:—Figure 1 is a more or less schematic representation, in most part in section, of a transmitter wherein the make-and-break and the condenser effect is produced, but refinements of construction are omitted. Fig. 2 is a face view of a back contact constructed in accordance with the present invention and wherein the showing may be considered as more or less exaggerated. Fig. 3 is a longitudinal section through a transmitter head with the invention applied, wherein the diaphragm is of the conductive-film membrane type. Fig. 4 is a plan view with parts omitted of a transmitter of the multi-tuned diaphragm type with one of the electrodes in the form of a conductive-film. Fig. 5 is a section on the line 5—5 of Fig. 4, with the supporting base omitted.

30 In the drawings two general types of transmitter are shown, in both of which a conducting film is provided as one of the electrodes.

In Figs. 4 and 5 is disclosed the multi-tuned metal diaphragm type, while in Figs. 1, 2 and 3 the disclosure is directed to the membrane type of diaphragm wherein the circuit may be completely broken mechanically on the movement of the electrodes away 40 one from the other, but wherein the condenser effect maintains the electrical continuity of the circuit. Both forms of the transmitter have parts in common, but as the forms of Figs. 1, 2 and 3 embody a 45 greater departure from the ordinary telephone transmitter than the form of Figs. 4 and 5, the following description will be directed first to the forms of Figs. 1, 2 and 3.

Referring more particularly to Fig. 1, 50 there is shown a support 1 carrying a foot member 2 on which is erected a post 3 in turn supporting a ring 4 engaging about a bead 5 surrounding one end of a mouth-piece 6 into which speech may be uttered, the word speech being used for convenience 55 of description to mean not only vocal, but other sounds, although customarily telephones are used in a great majority of instances for speech.

60 Clamped between the ring 4 and bead 5 is a membrane 7 of any suitable flexible material, of which rubber may be taken as an example, but without confining the invention to the use of rubber alone. One side 65 of the membrane 7 has applied thereto a

film 8 of conducting material such as gold-leaf, or silver-leaf, or platinum, or aluminum paint, or graphite, or other forms of carbon, although gold leaf is usually to be preferred. The conducting film 8 is sufficiently extensive to be confined against the ring 4 which may be made of metal and serve as a conductor, the foot 2 being provided with a binding post 9 to which one lead 10 of the circuit may be connected. 75

Mounted on the base 1 in proper relation to the foot 2 are guides, of which one guide 11 is shown, and these guides receive a foot 12 from which rises a post 13 terminating in a disk or plate 14 having a surface parallel 80 with the film 8. The base 1 carries a screw 15 passing through the post 13, whereby the latter may be adjusted toward and from the post 3 to bring the plate 14 into the desired relation with the film 8 of the diaphragm 7. 85 Fast to the post 13 is a binding post 16 to which the other lead 17 of the circuit may be connected, and the circuit is customarily charged with a current of high amperage and low potential. That face of the plate 14 90 toward the film 8 is scored or cross-hatched, or suitably formed so as to present a multitude of points or projections of minute area toward the film 8, not only to prevent sticking between the film 8 and plate 14, but to 95 provide a multitude of discharge points.

In Fig. 1 the distance between the film 8 when at rest and the plate 14 is exaggerated, for in practice the distance is such that while when the diaphragm is at rest the circuit is broken between the film and plate, the vibratory movements of the diaphragm when toward the plate will cause contact between the film 8 and plate 14, thereby then establishing the circuit to be immediately 105 afterward broken by the return movement of the diaphragm.

In order that the diaphragm may respond in a lively manner to sound waves, it is made more or less taut, so as to have a natural 110 rate of vibration determined by the character of the sounds to be transmitted, and as this rate of vibration may be brought about not only by the tautness of the diaphragm, but by its thickness and character and other 115 conditions, no special directions can be given as to this matter, but the mounting of the diaphragm to produce the natural rate of vibration is a matter well within the province of one well familiar with the principles 120 of acoustics.

While the structure of Fig. 1 when properly adjusted will operate for the transmission of speech it lacks certain of the refinements of a commercial type, but will answer 125 for an understanding of this part of the invention so far as the electrical actions are concerned.

Suppose that the instrument of Fig. 1 is connected up in a telephone circuit in the 130

usual manner of connecting a telephone transmitter, then when speech is uttered into the mouthpiece 6 the diaphragm 7 is set into vibration in accordance with the uttered sounds. The film 8 is moved against the plate 14 in one phase of its movement and out of contact and away from the plate 14 in the other phase of its movement, thus establishing make-and-break conditions, 5 with the resultant great variation in resistance in the transmitter circuit with correspondingly great variations in the line and commensurate variations at the distant receiver. As is well known such conditions 10 will not result in the intelligible transmission of speech. There are, however, two expanded conducting surfaces represented by the film 8 and plate 14, which during the period of break are separated by a very 15 thin air space, while the roughened surface of the plate 14 presented toward the film 8 provides a multitude of fine points from which the current will flow. On the break of contact condenser conditions are established, 20 so that the electrical continuity of the circuit is maintained by electrostatic induction. The result of this action is that there is produced upon the local circuit pulsating currents closely approaching in degree of 25 variation currents produced by make-and-break conditions, but still without any break in the circuit when considered electrically, while the sound produced at the receiver has all the characteristics of the original sound 30 uttered against the transmitter and is reproduced with greater intensity and more clearly and naturally than is the case when transmitters as ordinarily constructed are employed. 35 While the structure shown in Fig. 1 is capable of practical operation certain refinements of construction are advantageous for commercial transmitters, and in Fig. 3 there is illustrated a structure well adapted for 40 commercial uses.

Mounted on a stem 19 through the intermediary of a pivot joint 20 is a head 21, the stem 19 representing either the post of a desk set, or the arm of a wall set, or any 45 other suitable support. The head 21, which may be of metal, or which may be made of other material, is usually approximately circular in outline, and is formed on one face with a recess 22 of appropriate diameter 50 communicating through an axial passage 23 with another recess 24 in that face of the head 21 remote from the recess 22, and of smaller diameter. 55

The recess 22 is bounded by an annular rib 60 25 having an outer rounded edge 26 and surrounding the rib 25 is an annular channel 27. The periphery of the head 21 exterior to the channel 27 is formed with screw threads 28 adapted to receive the inner threaded wall 65 of a flange 29 extending axially from one

face of a cap 30 of a size to inclose the recess 22 and groove 27. The cap 30 is formed at the central portion with a mouthpiece 31 of the usual flaring type common in telephone instruments, and whether or not the head 21 70 be formed of metal it is customary to construct the cap 30 of hard rubber or some similar material.

The outer end of the recess 21 is covered by a membrane 32 of elastic rubber or other 75 suitable material having that face toward the recess 22 covered with a film 33 of some suitable conducting material of which gold-leaf is to be preferred, since it is inert to atmospheric and other like influences, and is 80 a good electric conducting material. Instead of gold, silver or platinum may be used, or aluminum or graphite may be employed, while operative results may be obtained from other conducting materials 85 capable of carrying the desired current, though the conductor be in the form of a film. The conducting film 33 is sufficiently extensive to engage the rounded portion of the rib 25 so as to make good electric contact 90 therewith, it being understood that this bead is made of conducting material, whether or not the head 21 be so made, but for convenience of description it will be assumed that the head 21 is of metal and the 95 rib 25 is also made of metal. The margin of the membrane diaphragm 32 is engaged between two clamping rings 34, 35 of any suitable material, say metal, and these rings may be double walled, as indicated, so that 100 the engaging portions may be made slightly elastic to grip the membrane, and one of the rings, say the ring 34, is formed with a channel 36 in which may be lodged anti-friction balls 37, so located as to be engaged by the 105 inner face of the cap 30. When the parts are assembled, and after the margin of the membrane diaphragm 32 is clamped between the rings 34 and 35, the latter are introduced into the channel 27 and then the anti-friction balls 37 are lodged in the channel 36 which operates as a ball-race-way, and then the cap 30 is screwed on to the head engaging the balls 37 and forcing the rings 34 and 35 into the channel 27, thus stretching 110 115 the membrane diaphragm 32 over the rib 25 until the desired tension is established in the diaphragm, whereby the latter may be tuned to any desired degree.

Extending through the passage 23 is a rod 120 38 surrounded by a sleeve 39 of insulating material, since the head 21 is made of metal. At one end the rod 38 carries a disk 14^a like the disk 14 of the structure shown in Fig. 1, and this disk 14^a has the face remote from 125 the rod 38 cross-hatched to form a multitude of closely associated projections 40, although these projections may be otherwise formed than by cross-hatching, such cross-hatching being in the form of grooves at appropriate 130

angles to cause the projections. The grooves may be quite fine and the projections quite minute, so that the free face of the disk 14^a has more or less the appearance of being 5 roughened, but the points of the projections should lie in as nearly one plane as may be and this plane should be as nearly parallel with the plane of the film 33 as may be, and likewise the points or projections of the disk 10 14^a should be as close as practicable to the film 33 without actual contact when the parts are at rest.

All the parts are shown exaggerated both 15 in size and position in Figs. 1, 2 and 3, this being rendered necessary by the limits of illustration and the separation of the conducting face of the diaphragm and the face of the disk contiguous to the diaphragm is greater in the showing of the drawings than 20 need be in practice, and the thickness of the film 33 and the size of the projections 40 are exaggerated.

While in the drawings the head 21 is shown as of considerable diameter, it is customarily in practice to make it of about the 25 diameter of telephone transmitters as usually employed in telephone sets.

That end of the rod 38 remote from the disk 14^a is threaded, as indicated at 41, and 30 extends into the recess 24. The threaded end 41 of the rod 38 receives a nut 42 formed on a spring washer 43, which in turn bears against another washer 44 which may be made of some insulating material, such as 35 mica, and this washer 44 engages the inner wall of the recess 25. Surrounding the sleeve 39 between the disk 14^a and the inner wall of the recess 22 is a spring 45 resting at the end remote from the disk 14^a against 40 a disk 46 of mica or other suitable insulating material lodged against the inner wall of the recess 22.

The outer end of the threaded portion of 45 the rod 32 has a binding post 47 applied thereto for the reception of a conductor 48 and to protect those parts of the apparatus lodged in the recess 24, the latter is provided with a cap 49 which may be held to the head 21 by screws 50 or in any other appropriate 50 manner, the conductor 48 being carried through a perforation 51 in the cap 49. The conductor 48 is included in one side of the usual local transmitter circuit, while the other side of this circuit includes a conductor 55 52 secured to the head 21 when this head is of metal or to the rib 25 when the head is of some other material, the purpose being to include the film 33 in one side of the circuit and the disk 14^a in the other side thereof, so that the film and disk constitute the 60 terminals of the local transmitter circuit.

When the parts are at rest the film 33 and 65 roughened face of the disk 14^a are separated by an air space of very small depth, so that when the diaphragm is set in vibration by

sound waves the film 33 is moved into contact with the many points 40, whereby on one phase of movement contact is made and increased to a maximum, and on the other phase of movement this contact is broken, 70 so that on this respect the transmitter is a make-and-break transmitter with a variable contact agreeable to the extent of vibration of the diaphragm on the one phase of movement of the diaphragm. On the break of 75 the circuit the extended surfaces of the disk 14^a and film 43 separated by a minute air space become in effect a condenser establishing electrostatic induction, so that there is no actual break in the electrical conditions, 80 the many fine points 40 contributing to the flow of current across the air gap without, however, the establishing of any minute arcs as often occur in the granular type of microphonic transmitter when heavy current is 85 passing and which give rise to the "flying" effect.

Practice has demonstrated that a much larger current may be employed with the transmitter of the present invention than 90 can be employed with the Blake or Hunnings type of transmitter without detrimental effect and with the advantage due to the employment of large currents.

The natural rate of vibration of the diaphragm 32 is established by turning the cap 30 to screw it on to or unscrew it from the head 21 to the requisite degree and the relation of the disk 14^a to the conducting face of the diaphragm is readily established by 100 means of the nut 42, the ball bearings 37 preventing any twisting of the rings 34 and 35 while the cap 30 is being turned to establish the desired adjustments.

Although the film 33 may be extremely 105 thin it presents a large surface and extensive contact at the rib 25, while the diametric extension of the disk 14^a is also considerable, wherefore ample conducting capacity is provided for the heavy current which may be 110 employed, and this current as before stated may exceed, without detrimental effect and with advantage, the current which it is possible to employ with prior commercial types 115 of transmitters.

Some, though not all, of the features of the transmitters of Figs. 1, 2 and 3 are retained in the transmitter of Figs. 4 and 5 where the condenser effect is not realized and where great variation of contact may be brought about by causing the make-and-break in part only and not throughout the sound responsive elements as occurs in Figs. 1 and 3.

Referring now more particularly to the 125 structure shown in Figs. 4 and 5 there is a base 53 on which is erected a post 54 terminating in an upstanding yoke 55 having at the free ends of the legs of the yoke bearings 56 for trunnions 57 on opposite sides of a 130

hollow body 58, this hollow body being comparatively flat and rounded at the edges with one side 59 extended in the form of a neck terminating in an expanded mouthpiece 60, the said mouthpiece communicating with an interior chamber 61 substantially coextensive with the body through the neck 59 by way of the passages 62, while diametrically opposite the neck 59 a passage 63 is formed through the edge wall of the body 58. One flat wall of the body 58 is in the form of a disk 64, the edge of which is threaded to fit like threads in the body portion, so that the disk 64 may be applied to or removed from the body at will, whereby access may be had to the chamber 61 when desired.

The body 58 and mouthpiece 60 as well as the removable member 64 may be made of metal or may be made of some material of an electrically insulating character. When the body member is made of metal there is secured to the center portion of the cover member 64 a block 65 of insulating material extending entirely through the member 64, while the opposite wall of the body member 58 has a like block 66 lodged therein.

The interior chamber 61 is sufficiently extensive to receive a disk 67 of insulating material, to the periphery of which there is applied a tube 68 of some material such as elastic rubber. This tube is an endless tube and may be so constructed as to present the characteristics of a pneumatic tire or the elasticity of the rubber alone may be depended upon for under some circumstances a simple ring of rubber will give good results. This rubber ring or tube is covered with a film 69 of some conducting material of which gold leaf is to be preferred, although silver or platinum will give good results and even aluminum or graphite may be employed, but not with such advantage as gold. The diameter of the rubber tube or ring 68 is greater than the thickness of the disk 67, so that the tube projects laterally beyond the plane of either face of the disk 67. Carried centrally by the disk 67 and projecting axially from opposite sides thereof are rods 70, 71, respectively, each secured to the disk 67 by an adjusting nut 72 next to the disk and another nut 73 more distant from the disk, the nuts 72 and 73 clamping between them a diaphragm 74, there being such a diaphragm on each side of the disk 67, while the diameter of the diaphragm, which is of metal, is such that its periphery engages the conducting film surface 69 of the tube or ring 68 throughout its circumference, the marginal portions of the two diaphragms being electrically connected when at rest by means of the film 69. The rods 70 and 71 are long enough to pass through the respective blocks 65 and 66, and exterior to these blocks the rods may receive

lock nuts 75 and each terminates in a binding post 76 to receive respective conductors 77, 78 of the local transmitter circuit.

When the structure is assembled, the rods 70 and 71 are secured to the disk 67 in axial relation thereto and project from opposite sides thereof. The tube or ring 68 properly coated with conducting material is then sprung upon the disk where its elasticity will hold it in place, the periphery of the disk being shaped to receive and retain the rubber ring. The nuts 72 are applied to the respective rods 70 and 71, and then the diaphragms 74 are placed upon the rods and are locked in place by the nuts 73. The cover member 64 having been previously removed, the diaphragm holder so far assembled is introduced into the chamber 61 through the opening left by the removal of the cover member 64, such opening being of sufficient size for the purpose. The rod 71 is passed through the block 66 and then the lock nut 75 is applied, after which the binding screw of the corresponding binding post 76 is inserted and the conductor 78 may be secured to the binding post either at this time or later. The cover 64 may now be screwed into place, the passage in the block 65 for the rod 70 being large enough for the purpose and then the corresponding clamp nut 75 may be applied, after which the conductor 77 may be attached to the corresponding binding post 76, it being understood that the diaphragms 74 have been properly adjusted before the assembling of the completed structure. The only rigid support for each diaphragm is at the center, while the peripheral portions of these diaphragms are slit toward the central portion of the diaphragm to form tongues 79 having different natural rates of vibration, and while each diaphragm may have more than one tongue tuned to respond to the same rate of vibration, a sufficient number of tongues are provided to practically cover the range of vibration of the fundamentals and overtones of a sufficient number of the sounds within the range of the normal human voice to cause vigorous selective response of portions of the diaphragm to such tones and overtones whereby the over tones particularly are not choked off, as occurs with the ordinary peripherally clamped diaphragm and the resultant transmission closely approaches in naturalness and purity of tone the sounds uttered at the transmitting end of the system.

The sound waves do not strike the diaphragms in a direction substantially perpendicular thereto as in the ordinary transmitter where the waves may rebound with resultant confusion, but in a manner guide over the diaphragms from the mouthpiece 60 where they enter by way of the passages 62 into the chamber 61 and finally emerge

at the passage 63 without the liability of rebound or reflection.

In the structure shown in Figs. 4 and 5 the movements of the tongues 79 may be sufficient to cause a break of the circuit at the tongues so violently vibrated but the circuit is not actually broken throughout the diaphragm since some of the tongues will always remain in contact with the conducting surface of the tube or ring electrically connecting the diaphragms.

The sound waves in acting upon the transmitter of Figs. 4 and 5 attack both diaphragms simultaneously, so that these diaphragms move in opposite directions, that is, they move toward the conducting film 69, together, and they move simultaneously away from such conducting film, so that there is produced a greater variation in resistance than occurs with the ordinary diaphragm, and this variation of resistance is augmented by the more violent movements of the attuned tongues which respond with increased amplitude to those sounds to which they are tuned. Moreover, the diaphragm being supported at the center only and free to vibrate at the margins is therefore more sensitive to the action of sound waves and the vibrations are correspondingly more pronounced, wherefore the impulses produced upon the line are more intense and the distant receiver is more vigorously acted upon than is the case in telephone systems as customarily installed.

In both forms of the transmitter shown in the drawings the contact is by way of a conductor film whether of metal or carbon in some form. Considering the membrane of Figs. 1 and 3, or the tube or ring of Figs. 4 and 5 as being made of rubber or some such material, the film of gold or other metal may be applied by first covering the diaphragm or the tube with a suitable size and then applying a metal either in the form of a thin foil or otherwise, or in the case of aluminum or graphite the conductive film may be produced by applying a substance mentioned in the form of a paint, or a solution of gun cotton may be applied to the rubber or other like surface in a manner similar to the production of incandescent lamp films and the gun cotton surface may then be flashed. Experience has demonstrated, however, that the results obtained from forms of carbon for the conducting film are not equal to those obtained from metal, while goldleaf appears to give the best results.

With the present transmitter packing is of course impossible irrespective of the position of the transmitter, since there are no loose particles present as in the granular microphonic element.

Moreover, in both forms of the transmitter as included in this invention the

weight of the parts to be moved by the sound waves is small as compared with the ordinary granular transmitter, wherefore the parts move more vigorously and the overtones or harmonics are not blotted out either actually or effectively.

With the transmitter of Fig. 3 the spring 45 may respond to the impact of the diaphragm, and in the structure shown in Figs. 4 and 5 the rubber ring or tube will yield slightly, so that in each case there is a yielding back contact. While in the structure of Figs. 1 and 3 there is a mechanical break of contact, electrical continuity of the circuit is maintained by electrostatic induction, and while in the structure of Figs. 4 and 5 there may be actual mechanical break of contact between some of the tongues and the conducting film, there are always some tongues in actual mechanical contact with the conducting film, wherefore the electrical continuity of the circuit is maintained, but the variation of contact may be very marked. Again, in the structure shown in Figs. 4 and 5 the selective capacity of the tongues cause the impress upon the transmission line of superposed polyphase currents customarily representing every component of the uttered sound, which in the vast majority of cases is the human voice.

In both forms of the transmitter the diaphragm may be extremely sensitive to the sound waves, while the conducting surface is of such large area that it is able to handle any desired amount of current which may be utilized to its full extent. Moreover, in the form of the transmitter shown in Figs. 4 and 5 the contact though actual may be exceedingly loose when the diaphragms are at rest, thus contributing to a great range in the variation of contact even to the actual breaking of the circuit at some of the tongues.

In the structure shown in Fig. 3 the parts moving under the impulse of the sound waves may be highly sensitive to sound waves and may be tuned. This admits of the provision of an instrument of the make-and-break electrostatic-induction type of transmitter with a plurality of diaphragms each differently tuned from the others and all associated, in sound receiving relation to a single mouthpiece, so that the same reinforcement of the components of sounds may be obtained as is present in the form of the invention shown in Figs. 4 and 5. It is feasible to provide as many as twelve diaphragms in conjunction with a single mouthpiece.

It is not necessary that the free face of the disk presented toward the conducting side of the membrane diaphragm in the structures shown in Figs. 1 and 3 should be cross-hatched or checkered or otherwise roughened in effect, but such formation of

said free face prevents cohesion of the disk and diaphragm and is, therefore, to be preferred. It is also advisable that the free face of the disk be highly polished before 5 being roughened, checkered or cross-hatched.

The membrane diaphragm need not be more than simply taut for the natural rate of vibration may be obtained by variations in thickness, diameter, tension or by the use 10 of dampers. The checkering, cross-hatching or roughening of the plate or disk constituting the back electrode is not only effective with respect to preventing cohesion, but increases the electrostatic condition and 15 striking distance of the current by presenting many sharp points to the opposite or movable electrode or contact.

Again, when the potential in the local transmitter circuit is considerable, as, for 20 instance, when the source of current comprises quite a number of cells in series, the membrane is very slightly pulled toward the back contact, whereby there is produced an electroscopic balance condition, wherefore 25 the action of the speech vibrations uttered against the diaphragm are correspondingly more effective because of the condition of unstable equilibrium established.

The transmitter of the present invention 30 differentiates from prior transmitters by several distinctive characteristics, among which may be named the mechanical or physical make and break without destroying the electrical continuity of the circuit where- 35 by great variation of resistance is obtainable and at the same time such variation is gradual and not sudden as would occur where the mechanical or physical break of the circuit is accompanied by a like break in the elec- 40 trical continuity of the circuit. The structure of the transmitter provides for an exceedingly great amplitude of vibration in a membranous diaphragm with a coextensive conducting film. The electrostatic pull on 45 the diaphragm which exists causes a readiness for instantaneous action and return to inaction. The checkered or scored back electrode presents an enlarged surface with many minute points of contact all in fixed 50 relation one to the other, which back electrode by its construction prevents cohesion of the vibratile electrode with it and also augments the electric capacity of the instrument. The construction also permits the 55 use of a large current distributed over a large surface so that arcing or other troubles met with in the ordinary granular transmitter when large currents are used are avoided.

60 This application is a continuation of my application No. 633,461, filed June 16, 1911, for a conductive film telephone transmitter.

What is claimed is:—

65 1. A telephone transmitter provided with two electrodes in face to face relation and

radially expanded, one of the electrodes being in the form of a non-conductive mem- 70 brane of flexible material covered on one face with a conductive film substantially coextensive with and firmly united to the membrane for vibration therewith under the action of sound waves, and the other electrode being of a radial extent to cause the two electrodes to serve as condenser plates of appreciable capacity, said electrodes being spaced apart by a distance less than the travel of one of them from rest under the impact of sound waves.

2. A telephone transmitter provided with electrodes movable into and out of contact 80 under the action of sound waves, one of said electrodes being in the form of a membrane covered by a conductive film and the other electrode being shaped to provide numerous points for contact with a film, said contact 85 points being in fixed relation one to the other.

3. A telephone transmitter provided with electrodes, one of which is in the form of a conductive film and the other of which 90 is laterally extended and formed with nu- merous points presented toward the film for contact therewith, one of said electrodes being responsive to sound waves to vibrate under the action thereof and having a range 95 of movement sufficient in one direction to cause contact between the film and more or less of the numerous contact points of the other electrode with varying pressure de- pending upon the sound waves acting there- 100 on, and also having a range of movement in the other direction sufficient to entirely disengage the electrodes.

4. In a telephone transmitter, a disk-shaped conducting member and another 105 member carrying a conducting film in close proximity to said conducting member, said members having their facing areas suffi- ciently extensive to establish an electrostatic relation between them, one of said members 110 being related to the other to vibrate under the direct action of sound waves into and out of contact with the other and to contact during its vibration toward the other to varying extents therewith.

5. In a telephone transmitter, a conduct- 115 ing film and a disk-shaped conducting mem- ber in close proximity thereto, said members having the areas of their facing portions suffi- ciently extensive to establish an electro- 120 static relation between them, the conducting film having a resilient backing, and one of said members being related to the other to vibrate under the action of sound waves into and out of contact with the other and to contact during its vibration toward the other to varying extents therewith.

6. In a telephone transmitter, a conduct- 125 ing member having a contact surface divided into a plurality of contacting parts in fixed 130

- relation one to the other, and a vibratile conductive film in close proximity to the conducting member and having a range of movement under the action of sound waves
- 5 to engage varying numbers of the contacting parts when moved theretoward and wholly disengaged from the contacting parts when moved in the other direction,
7. A telephone transmitter having electrodes in electrostatic inductive relation and out of mechanical contact when at rest and related to make physical electrical contact when vibrating under the action of the sound waves to be transmitted.
- 10 8. A telephone transmitter having electrodes provided with extended conducting surfaces in electrostatic inductive relation one to the other and also located one with reference to the other to make physical electrical contact when vibrated under the action of sounds to be transmitted.
- 15 9. A telephone transmitter provided with a membrane diaphragm responsive to sound waves uttered against it and provided on the surface remote from that receiving the sound waves with a conducting film, and a back electrode in electrostatic inductive relation to the conducting film on the diaphragm and within the range of movement
- 20 of the conducting film under the action of sound waves to cause physical electric contact between the film and back contact.
- 25 10. A telephone transmitter provided with a membrane diaphragm responsive to sound waves uttered against it and provided on the surface remote from that receiving the sound waves with a conducting film, and a back electrode in electrostatic inductive relation to the conducting film on the diaphragm and within the range of movement of the conducting film under the action of sound waves to cause varying physical electric contact between the film and back contact, the back contact having that face presented toward
- 30 the conducting film provided with numerous contact points in fixed relation one to the other.
- 35 11. A telephone transmitter provided with a non-conductive membrane diaphragm supported at the margin and provided on one face with a conducting film coextensive with the diaphragm to its marginal portion, and a radially extended back contact in close relation to but normally out of contact with the conductive film and within the range of movement of the diaphragm under the action of sound waves to make contact therewith when moved theretoward and break contact therewith when moved away
- 40 therefrom under the action of sound waves to be transmitted.
- 45 12. A telephone transmitter provided with a non-conductive membrane diaphragm supported at the margin and having one face covered by a conducting film extending
- 50 to the marginal support, and a back contact in operative relation to the conducting film and extended toward the marginal portion of the latter, said back contact having the face presented toward the conducting film 70 formed into a multitude of fixed pointed projections constituting contact points, the diaphragm having a range of movement under the impact of sound waves to cause it to engage varying numbers of the projections when moved toward the back contact and to wholly disengage therefrom when moved away from the back contact.
- 55 13. A telephone transmitter provided with a membrane diaphragm having a conducting film on one face, a back contact in operative relation to the conducting film, a marginal support for the diaphragm, concentric radially elastic clamping rings for gripping the marginal portion of the diaphragm, said 80 rings being of greater diameter than the marginal support for the diaphragm, and a cap member for the transmitter movable into operative engagement with the clamping rings to force them axially with relation 85 to the diaphragm support to place the diaphragm under radial stress.
- 60 14. A telephone transmitter comprising a body member having a rib outstanding from one face with a channel exterior to and surrounding said rib, and said body member being screw threaded exterior to the channel, a cap member having a threaded flange adapted to the screw threads of the body member and of a size to cover the rib and channel, a membrane diaphragm provided on one face with a conducting film and of a 90 diameter to engage the rib and enter the channel exterior thereto, concentric clamp rings adapted to receive between them the 95 peripheral portion of the diaphragm and of a size to enter the channel outside the rib, said rings being adapted to be engaged by the cap to stretch the diaphragm over the rib, and a back contact carried by the head 100 of the body member in operative relation to the film on the diaphragm.
- 65 15. A telephone transmitter comprising a body member having a rib outstanding from one face with a channel exterior to and surrounding said rib and said body member being screw threaded exterior to the channel, a cap member having a threaded flange adapted to the screw threads on the body member and of a size to cover the rib and channel, a membrane diaphragm provided on one face with a conducting film and of a diameter to 105 engage the rib and enter the channel exterior thereto, concentric clamp rings adapted to receive between them the peripheral portion of the diaphragm and of a size to enter the channel outside the rib, said rings being adapted to be engaged by the cap to stretch the diaphragm over the rib, and a back contact carried by the head 110 of the body member in operative relation to the film on the diaphragm.
- 70 16. A telephone transmitter comprising a body member having a rib outstanding from one face with a channel exterior to and surrounding said rib and said body member being screw threaded exterior to the channel, a cap member having a threaded flange adapted to the screw threads on the body member and of a size to cover the rib and channel, a membrane diaphragm provided on one face with a conducting film and of a diameter to 115 engage the rib and enter the channel exterior thereto, concentric clamp rings adapted to receive between them the peripheral portion of the diaphragm and of a size to enter the channel outside the rib, said rings being adapted to be engaged by the cap to stretch the diaphragm over the rib, and a back contact carried by the head 120 of the body member in operative relation to the film on the diaphragm.
- 75 17. A telephone transmitter comprising a body member having a rib outstanding from one face with a channel exterior to and surrounding said rib and said body member being screw threaded exterior to the channel, a cap member having a threaded flange adapted to the screw threads on the body member and of a size to cover the rib and channel, a membrane diaphragm provided on one face with a conducting film and of a diameter to 125 engage the rib and enter the channel exterior thereto, concentric clamp rings adapted to receive between them the peripheral portion of the diaphragm and of a size to enter the channel outside the rib, said rings being adapted to be engaged by the cap to stretch the diaphragm over the rib, and a back contact carried by the head 130 of the body member in operative relation to the film on the diaphragm.

tive relation to the film of the diaphragm, said back contact having the face presented toward the film provided with numerous points.

5 16. A telephone transmitter comprising a body member having a rib outstanding from one face with a channel exterior to and surrounding said rib, and said body member being screw threaded exterior to the channel, a cap member having a threaded flange adapted to the screw threads on the body member and of a size to cover the rib and channel, a membrane diaphragm provided on one face with a conducting film and of a 10 diameter to engage the rib and enter the channel exterior thereto, concentric clamp rings adapted to receive between them the peripheral portion of the diaphragm and of a size to enter the channel outside the rib, 15 said rings being adapted to be engaged by the cap to stretch the diaphragm over the rib, and a back contact carried by the head in operative relation to the film of the diaphragm, said back contact having the face 20 presented toward the film provided with numerous points, and said back contact having an adjustable mounting in the head for determining its relation to the film of the diaphragm.

25 17. A telephone transmitter provided with a suitable head, a screw cap adapted to the head and provided with a sound receiving mouthpiece, and a membrane diaphragm adapted to the head between the cap member and said head, the head member having a support for the marginal portion of the diaphragm, and holding means for the peripheral portion of the diaphragm outside the support in the path of the cap member for 30 engagement thereby to readily tension the diaphragm, said peripheral holding means for the diaphragm being provided with anti-friction devices between it and the cap.

35 18. A telephone transmitter having normally separated electrodes constructed and associated to make variable contact under the action of sound waves and to maintain the electrical continuity of the circuit, when 40 out of mechanical contact by electrostatic induction.

45 19. A telephone transmitter having normally separated electrodes constructed and associated to make variable contact under the action of sound waves and to maintain the electrical continuity of the circuit, when 50 out of mechanical contact, by electrostatic induction, one of the electrodes having its active surface in the form of a conducting film and the other electrode in the form of 55 a plate with a multi-pointed face presented toward the film.

60 20. A telephone transmitter having a vibratory sound responsive electrode and a back electrode constructed and arranged to cause a range of vibration of the sound re-

sponsive electrode, under the action of sound waves, into contact with the back electrode and out of contact therewith and in the latter case establish electrostatic inductive relations between the electrodes.

65 21. An instrument of the character described comprising opposed condenser elements one of which is mounted for vibration into and out of physical or mechanical contact with the other, and said condenser elements being associated to constitute electrodes for an electric circuit.

70 22. An instrument of the character described comprising condenser elements one of which is in the form of a conducting film with a vibratile membranous support, and the other in the form of a conducting plate having the surface scored or checkered to present many points in fixed relation one to the other toward the conducting film of the other element, and said condenser elements being associated and the one with the vibratile support having a range of vibration to cause it to contact with the conducting plate, whereby the condenser elements 75 constitute electrodes for an electric circuit.

80 23. An instrument of the character described comprising opposed condenser elements one of which is vibratile and movable into and out of contact with the other and provided with an expanded conducting surface and the other of which is in the form of a conducting plate having a surface in operative relation to the conducting surface of the other element, which surface of 85 the second named element is scored or checkered to present many pointed portions toward the conducting surface of the first named element.

90 24. A telephone transmitter having a diaphragm tuned to respond sympathetically to the sounds to be transmitted, and a laterally expanded back contact in electrostatic relation to the diaphragm and located within engaging distance of the diaphragm 95 on vibrations of the latter under the action of sound waves in a direction toward the back contact.

100 25. A telephone transmitter having a diaphragm tuned to respond sympathetically to the sounds to be transmitted, and a laterally expanded back contact in electrostatic relation to the diaphragm and located within engaging distance of the diaphragm 110 on vibrations of the latter under the action 105 of sound waves in a direction toward the back contact, the diaphragm and back contact having the adjacent surfaces conducting to electric current and constituting the electrodes of a condenser when out of contact, one of said surfaces being checkered or roughened to present numerous conducting points toward the other.

115 26. An instrument of the character described having laterally expanded electrodes 120

in opposed relation and normally separated by an air space, said electrodes being of conducting material and one of the electrodes being vibratile and in close relation to the other to cause the electrodes when charged to be in a state of electro-static balance.

In testimony, that I claim the foregoing

as my own, I have hereto affixed my signature in the presence of two witnesses.

ANDREW PLECHER.
